US0D1031793S

(12) **United States Design Patent** (10) **Patent No.:** **US D1,031,793 S**
(45) **Date of Patent:** **** Jun. 18, 2024**

(54) **SEPARATING GRATE**

(71) Applicant: **CALMER HOLDING COMPANY, LLC**, Lynn Center, IL (US)

(72) Inventors: **Daniel Wallerstedt**, Lynn Center, IL (US); **Marion Calmer**, Lynn Center, IL (US)

(73) Assignee: **CALMER HOLDING COMPANY, LLC**, Lynn Center, IL (US)

(**) Term: **15 Years**

(21) Appl. No.: **29/866,136**

(22) Filed: **Aug. 30, 2022**

(51) **LOC (14) Cl.** **15-03**

(52) **U.S. Cl.**

USPC **D15/28**

(58) **Field of Classification Search**

USPC D8/1, 7, 8; D15/17, 28, 29

CPC A01F 12/26; A01F 12/24; A01F 12/28;

A01F 7/06; A01D 41/12

See application file for complete search history.
